CLAIM

The ornamental design for a walker tray, as shown and described.

DESCRIPTION

FIG. 1 is a perspective view of a walker tray showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof with the attaching arms in open position; and,

FIG. 7 is a bottom plan view thereof with the attaching arms in open position.

The broken line showing in FIG. 1 is for illustrative purposes only and forms no part of the claimed design.
